Atty.

UNITED STATES PATENT OFFICE.

JOHN W. WALLACE, OF ROCK ISLAND, ILLINOIS.

MOLDER'S CHAPLET.

Application filed June 4, 1924. Serial No. 717,676.

This invention relates to molder's chaplets used in a mold to support and position a core in proper relation to the walls of the mold.

5 One of the purposes of my invention is to provide an improved molder's chaplet which is adjustable to accommodate flat, angular and curved surfaces.

Another purpose is to provide a chaplet 10 having one or more bridge-shaped core-engaging portions connecting a pair of mold-engaging portions separated by a vent opening reaching from side to side of the chaplet. This gives maximum vent space and 15 permits the mold-engaging portions to be relatively adjusted by flexing the connecting bridge-pieces. Another purpose is to provide a molder's chaplet of the character described formed of a single piece of sheet 20 metal, the bridge-pieces of which may be drawn to variable depths to provide an unusually wide range of sizes.

Still another purpose is to provide a molder's chaplet having bridge-pieces reenforced longitudinally in a particularly advantageously manner for strengthening purposes and for aiding in holding a core in position.

Other objects and attendant advantages 30 will be apparent to those skilled in this art as the invention becomes better understood by reference to the following description when considered in connection with the accompanying drawings, in which—

35 Figure 1, is a vertical section through a mold showing a number of chaplets embodying my invention, holding a core in position;

Fig. 2, is an enlarged end elevation of a molder's chaplet embodying my invention;

40 Fig. 3, is a top view of the chaplet;

Fig. 4, is a section taken on the line 4—4 of Fig. 3, showing the mold and core-engaging portion flat instead of curved as in Fig. 2; and

45 Fig. 5, is a detail section taken on the line 5—5 of Fig. 4.

Referring more particularly to the drawings, it will be observed that I have in the preferred embodiment shown my improved 50 molder's chaplet formed of a single piece of sheet metal stamped or pressed to shape and adapted to be flexed as will be presently apparent for accommodating different shapes of molds and cores.

55 In the embodiment shown in Fig. 3 the chaplet is rectangular in form and has a

pair of mold-engaging portions designated generally by 6 and 7 which are connected by one or more (two at present) bridge-pieces each providing legs 8 and an intermediate 60 core-engaging portion 9. The mold-engaging portions are separated from side to side by a vent opening 11. By pressing the bridge-pieces out of the body of sheet metal additional vent openings 12 are provided 65 reaching into the mold-engaging portions. This construction provides comparatively large vent area so that the chaplet is least obstructive to the escape of vapors and gases and so that the molten metal may flow 70 through the openings 11 and 12 and quickly fuse the chaplet.

The mold and core-engaging portions are preferably parallel or substantially so and may be either curved as shown in Fig. 2 to 75 fit the arcuate surfaces of a mold 13 and core 14 as shown in Fig. 1, or flat as shown in Fig. 4 to fit flat mold and core surfaces, or irregular or angular as may sometimes be required. By reason of the construction disclosed the mold-engaging portions may be adapted or positioned by flexing either the core-engaging portions or the legs 8 or both, if required, to suit the particular case 80 at hand. Furthermore, the chaplet is not 85 limited as to distance between the core and mold-engaging portions because by cutting out a piece of the body part transversely from side to side thereof to form the vent opening 11 the bridge-pieces may be drawn 90 or pressed out to any depth within reasonable limits, whereas in previous constructions the depth was limited by a draw of the metal. It will be manifest that a wider or narrower transverse portion may be cut 95 out, thus permitting a corresponding depth of bridge-piece or a wider or narrower vent separating the mold-engaging portions. The variation in depth of the bridge piece may be secured by bending the diagonally 100 extending legs 8 at the core and mold portions of the chaplet.

The bridge-pieces shown have parallel sides and are at present formed by splitting the flank or body piece from which the 105 chaplet is formed, lengthwise in the operation of pressing out such pieces. These bridge-pieces may however be otherwise formed and the sides need not necessarily be parallel. Furthermore any number of 110 bridge-pieces may be embodied in a chaplet to suit different requirements. In the pre-

ferred form of my invention the bridge-pieces are reenforced longitudinally by pressing them to channel-shape in cross section as shown in Fig. 5. This provides narrow spaced core-engaging surfaces which serve especially well in their holding contact with the mold.

While in practice the chaplets are made in different shapes and sizes, the present invention enables the production of a greater variety of sizes and shapes and also permits the chaplet to be adjusted by flexing to suit particular requirements or as a substitute for chaplets of greater or less depth.

15 The chaplets are especially adapted for adjustment to flat and curved planes and to cores of different diameters.

It is believed that the foregoing conveys a clear understanding of the objects preferred above and while I have illustrated but a single working embodiment of my invention it should be understood that many changes might be made in sizes and shapes of the chaplet without departing from the spirit and scope of the invention as expressed in the appended claims in which—

I claim:

1. A molder's chaplet comprising a single piece of sheet metal having parallel strips 30 pressed out at one side leaving vent openings and providing core-engaging portions

joined at opposite ends to the body proper, the latter being split from side to side transverse to and intermediate the ends of said pressed out portions providing vent openings in addition to those provided by said pressed out portions.

2. A molder's chaplet formed from a blank of sheet metal to provide a core-engaging portion and a mold-engaging portion connected together in spaced relation, one of said portions comprising a pair of U-shaped sections spaced to provide vents therebetween and the other of said portions being in the form of a strip joined with said U-shaped sections by legs extending therefrom and joined to said U-shaped sections between the arms thereof.

3. A molder's chaplet formed from a blank of sheet metal to provide a core-engaging portion and a mold-engaging portion connected together in spaced relation, one of said portions comprising a pair of E-shaped sections spaced to provide vents therebetween and the other of said portions comprising a pair of strips spaced apart to leave a vent therebetween and joined with said E-shaped sections by legs extending therefrom and joined with the E-shaped sections between the arms thereof.

JOHN W. WALLACE.
